UNITED STATES PATENT OFFICE

GUSTAV O. BRANDT, OF DETROIT, MICHIGAN, ASSIGNOR TO L. A. YOUNG SPRING & WIRE CORPORATION, OF DETROIT, MICHIGAN

METHOD OF ASSEMBLING SPRING STRUCTURES

Application filed May 17, 1928. Serial No. 278,578.

The main object of this invention is to provide a method of assembling spring structures in which coiled spring tie members are connected to the coacting parts, such as body 5 springs, in a manner preventing relative movement thereof.

A further object is to provide a method having these advantages which results in economy in forming and assembling the parts.

Objects pertaining to details and economies 10 of my improved method of assembling spring structures will definitely appear from the detailed description to follow. The invention is defined in the claims.

15 A structure by means of which I carry out my improved method of assembling spring structures is clearly illustrated in the accompanying drawing, in which:

Fig. 1 is a fragmentary side elevation of 20 a spring structure assembled in accordance with my improved method.

Fig. 2 is a fragmentary view of an assembling or clip applying tool which I preferably employ in my improved method, the 25 same being partially in longitudinal section on line 2—2 of Fig. 3.

Fig. 3 is a transverse section on line 3—3 of Fig. 2.

Fig. 4 is a fragmentary plan view of one 30 of the tie members employed by me.

Fig. 5 is a fragmentary plan view of one of the tie members as it would appear after the offset has been formed therein during the assembling operation.

35 Fig. 6 is a perspective view of a modified form of clip which may be employed in lieu of the wire clip shown in Figs. 1, 2 and 3.

The assembled structure in the embodiment 40 illustrated comprises double helically coiled body springs 1 and connecting top and bottom cross tie members 2. These tie members 2 are coiled springs having coils of uniform diameter.

The tie members are arranged in tangential 45 relation to the springs and secured thereto by means of clips 3 which are formed of wire and are preferably those such as shown in my co-pending application for Letters Patent filed concurrently herewith, Serial No. 278, 50 576.

In the application of these clips I provide a tool designated generally by the numeral 4 which is also the subject matter of an application for Letters Patent Serial No. 278,575 filed concurrently herewith and is described in detail in such application. This tool is provided with jaw members 5 having opposed jaws with curved faces 6, one of the jaws having forwardly projecting shoulders 7 which lie at the outside of the planes of the sides of the coacting jaw so that, when the jaws are closed to close the clip, the portion 8 of the tie member embraced by the clip is laterally offset as shown in Fig. 3, thereby providing shoulder-like stops in the tie member preventing longitudinal movement of the clip on the tie member or of the tie member within the clip.

This simultaneous closing of the clip and offsetting of the tie member enables the positioning of the springs at any desired point; that is, it is not necessary that tie members having specially spaced offsets be employed. Further, the clip is brought into exact or definite relation to the offset and the parts 75 vary securely retained.

In Fig. 6 I illustrate a sheet metal clip 9 which may be substituted for the wire clip shown in Figs. 1, 2 and 3.

I have not attempted to illustrate or describe the various forms of spring structures for the assembly of which my improved method is well adapted, as it is believed that this disclosure will enable those skilled in the art to embody or adapt my improvements as may be desired.

Having thus described my invention what I claim as new and desire to secure by Letters Patent is:

1. The method of assembling coiled body springs and coiled spring tie members having coils of uniform diameter into a spring cushion structure consisting of positioning a coiled spring tie member in tangential juxtaposition to a coil of a body spring, applying a clip adapted to embrace both the coiled spring tie member and the coil of the body spring, and closing the clip upon the parts and simultaneously offsetting the portion of the coiled spring tie member embraced by the 100

clip providing shoulders therein at each side of the clip.

2. The method of assembling coiled spring tie members having coils of uniform diameter and coacting parts of a spring structure consisting of positioning the coiled spring tie member in juxtaposition to the coacting part, applying a clip adapted to embrace both the coiled spring tie member and such coacting part, and closing the clip and simultaneously offsetting the portion of the coiled spring tie member embraced by the clip thereby providing stop shoulders at each side of the clip preventing longitudinal movement of the tie member within the clip.

3. The method of assembling coiled body springs and coiled spring tie members consisting of positioning a coiled spring tie member in tangential juxtaposition to a coil of a body spring, applying a clip adapted to embrace both the coiled spring tie member and the coil of the body spring, and closing the clip upon the parts and simultaneously offsetting a portion of the coiled spring tie member embraced by the clip.

4. The method of connecting coiled spring members and coacting parts consisting of positioning the coiled spring member in juxtaposition to the coacting part, applying a clip adapted to embrace both the coiled spring member and such coacting part, closing the clip and simultaneously offsetting the portion of the coiled spring member embraced by the clip.

35 In witness whereof I have hereunto set my hand.

GUSTAV O. BRANDT.
